Patented Aug. 23, 1921.

UNITED STATES PATENT OFFICE.

THOMAS L. B. LYSTER AND KENNETH E. STUART, OF NIAGARA FALLS, NEW YORK,
ASSIGNORS TO HOOKER ELECTROCHEMICAL COMPANY, OF NEW YORK, N. Y., A
CORPORATION OF NEW YORK.

APPARATUS FOR ELECTROLYZING SOLUTIONS.

1,388,474.

Specification of Letters Patent. Patented Aug. 23, 1921.

Application filed August 13, 1920. Serial No. 403,326.

To all whom it may concern:

Be it known that we, (1) THOMAS L. B. LYSTER and (2) KENNETH E. STUART, citizens of the United States, residing at Niagara Falls, in the county of Niagara and State of New York, have invented certain new and useful Improvements in Apparatus for Electrolyzing Solutions, of which the following is a specification.

10 This invention relates to the electrolytic decomposition of solutions, and more particularly to the electrolytic decomposition of sodium chlorid solutions in cells of the diaphragm type, a primary object of the 15 invention being to provide an improved apparatus for supplying to a cell, or usually to a large number of similar cells, a constant volume of electrolyte in unit time.

According to the invention in its preferred 20 embodiment the electrolytic cells receive in unit time a feed of a constant volume of electrolyte, for example an aqueous solution of sodium chlorid, said electrolyte carrying salt (typically sodium chlorid) in excess of 25 the amount normally soluble therein at the operating temperature, this excess of salt being of course present in solid phase at the moment of introduction of the electrolyte into the cell. However, our invention is not 30 restricted to such supply of salt in solid phase, inasmuch as certain of the benefits of the invention may be secured without this procedure.

In the practical operation of the invention, the quantity of salt thus supplied in solid phase is nearly but not quite sufficient to maintain the brine within the cell in a condition of complete saturation at the operating temperature: an excess of solid salt 40 above the quantity required for the saturation of the electrolyte within the cell should however be carefully avoided, as leading to the clogging of the diaphragm and otherwise interfering with the smooth conduct of 45 the operation.

In explanation of the desirability of supplying salt in solid phase to an electrolytic cell, it may be explained that it is a well established fact that if unsaturated brine is

fed to an electrolytic cell of the diaphragm type at the rate necessary merely to maintain percolation through the diaphragm, without an overflow, the gravity of the brine within the cell falls below that of the feed brine by a definite amount, which is dependent upon the percentage of decomposition. For example in a special case, operating under conditions as above, the brine within the cell was found to contain on the average 254 grams of salt per liter, although the feed brine during the same period contained 285 grams per liter. The dilution within the cell was therefore approximately to 89% of the original concentration. The explanation of this phenomenon appears to be that a certain proportion of the water is left behind upon the anode side of the diaphragm. The lower gravity thereby resulting lessens the viscosity of the solution and increases the percolation through the diaphragm, so that the operation of the cell soon becomes stabilized: but the specific gravity of the solution within the cell is permanently lowered. This is objectionable as tending not only to a higher operating voltage but to a lower concentration of caustic solution.

It is now established that the above described dilution of the brine is a function of the quantity of caustic produced; and that for every 100 grams of caustic delivered from the cell approximately 180 grams of water are left behind in the cell. If, for example, the feed brine contains 292.5 grams of sodium chlorid per liter, and the per cent. of decomposition is 50, this will amount to about 21% of the total water delivered to the cell with the inflowing brine. If it were possible to discharge this water from the anode side of the cell, the amount of water to be evaporated from the caustic would of course be correspondingly reduced: but the same object may be attained by keeping the concentration of the liquor within the cell approximately up to that of the feed liquor; or in other words as near as practicable at the saturation point.

An obvious method of maintaining the

concentration of the brine within the cell would appear to be the maintenance within the cell of a supply of salt sufficient for this purpose, and such procedure has been frequently proposed. This has proven impracticable, however, by reason of the tendency of the excess of salt to obstruct the diaphragm and otherwise to interfere with the operation of the cell; and it has been established that only such quantity of salt may be added as will, from a practical operating viewpoint, pass immediately into solution, the brine within the cell being at all times kept safely below the saturation limit at the operating temperature.

For a full understanding of the invention reference is made to the accompanying drawings illustrating a typical system in accordance with our invention, it being however understood that the invention is not restricted to the particular means chosen for illustration.

In said drawings:

Figure 1 is a diagrammatic elevation, partly in section, of a typical circulating and feeding system; Fig. 1^a being a plan view of the constant level tank 6;

Fig. 2 is a partial section of the same on a slightly enlarged scale on line 2—2 of Fig. 1; and

Figs. 3, 4, and 5 are detail sectional views of various types of feed nozzles which may be employed.

Referring to Figs. 1, 1^a and 2, 2 represents the brine storage tank; 3 the salt hopper containing fine granulated salt such as may be obtained by evaporation of the caustic liquor produced in the operation of the cells; 4 the mixing and agitating tank; 5, 5, 5, 5 the electrolytic cells; and 6 the level-regulating tank.

The tank 4 is filled with brine from the tank 2 by opening the valve 7. 8 is a brine-metering device which may be power-driven or may take the form of a geared rotor pump of the Root blower type, as more clearly illustrated in Fig. 2. The brine flowing through this metering device turns the rotor 9, which drives the sprocket 10, and, through chain 11, the large sprocket 12, the latter revolving a double-flight worm conveyor 13 which extends throughout the length of the salt hopper at the bottom thereof. This worm feeds the dry salt forward into the vertical open-ended pipe 14. The stream of brine from tank 2 is likewise directed into the pipe 14, where it washes the salt out of the worm as fast as it is fed forward, and carries it through the screen 15 and chute 16 into the mixing and agitating tank 4. There is therefore in the operation of this device, a fixed relation between the displacement of the brine-meter and the salt feed; so that a definite and con-

trollable quantity of salt can be fed for a given quantity of brine. The feed ratios may be adjusted as desired by a proper choice of sprockets 10 and 12.

It will be understood that the tank 2 might be filled with water or weak brine, and by feeding the proper quantity of solid salt a saturated, under-saturated or over-saturated brine can be delivered into tank 4 at will. For the purpose of the present invention, however, brine carrying an excess of salt in solid phase will usually be required; and it is generally preferable to obtain this by filling the tank 2 with brine having a specific gravity in the neighborhood of 1.2, and adding through the hopper 3 the salt necessary to provide the required excess.

In the system chosen for illustration the tank 4 is provided with a centrifugal pump 17 driven by a motor 18. The intake 19 of the pump 17 is located close to the bottom of the tank 4, and agitators 20 are mounted upon the vertical pump shaft. The delivery pipe 21 from pump 17 is carried over the cells 5 and terminates in an elbow 22, located within the level-regulating tank 6 and directed tangentially near the bottom thereof (see Fig. 1^a). 23 is the overflow inlet leading to the return pipe 24, terminating in an elbow 25 which may be directed tangentially near the bottom of tank 4.

By means of the pump 17 and the pipes 21 and 24 a rapid circulation of the salt suspension is maintained. Thereby the mixture in the tank 4 is kept in violent agitation and the undissolved salt is maintained in suspension during its flow to the tank 6 and return. 26 indicates a screen which may be placed across the tank 6 between the inflow and outflow to trap any foreign matter which may find its way into the system. A 20-mesh screen has proven satisfactory for this purpose, being sufficiently coarse to permit free passage of the fine solid salt, while sufficiently fine to remove any foreign matter that would be liable to interfere with the feed of the brine to the cells or with the operation of the latter.

Above each cell 5 is provided a feeding orifice or nozzle 27. A simple form of such orifice is illustrated on an enlarged scale in Fig. 3, comprising a calibrated glass tube 28 let into the pipe 21 through a rubber stopper by means of a T 29. The stream of brine from the tube 28 is directed into a glass T 30, which discharges in turn into the cells, for example through lengths of rubber hose 31, connected with earthenware well-pipes 32, which extend to a point well below the liquid level. Naturally any preferred device may be used for conveying the salt suspension to the cells or distributing it therein.

The hydrostatic head upon the orifice 27

is determined by the level of the liquid in the tank 6. This may be adjusted as desired by changing the effective height of the overflow pipe 23, which can conveniently be done 5 by screwing different lengths into the coupling 33. So long as the level in the tank 6 is maintained constant, the orifice 28 will feed a constant quantity of brine in unit time, this brine carrying therewith any desired 10 excess of suspended salt. This rate of feed is unaffected by the level of the liquid within the cell 5 or by the gas pressure therein.

Fig. 4 illustrates a stream-line type of orifice, screwed flush into the pipe 21 and terminating in a succession of tapered nozzles 34, screwed one upon the other, each successive nozzle being slightly smaller than the preceding one with the result that together 20 they form a uniformly tapering orifice of which the aperture may be closely regulated.

The types of orifice illustrated in Figs. 3 and 4 are not affected by the velocity of the flow in pipe 21, except as the resistance to 25 such flow creates added static pressure. Thus if the pipe 21 be horizontal, the orifice leading to the cell farthest from the tank 6 will be under a higher static pressure than that of the cell nearest this tank, by the amount of 30 the pressure necessary to overcome the resistance offered by the walls of the pipe 21 to the flow of the salt suspension therein. In order to equalize the static head on the several orifices, and thereby to equalize the flow 35 through these orifices, the pipe 21 is preferably inclined toward the regulating tank 6 as illustrated in Fig. 1. It is very easy to determine experimentally the degree of inclination necessary by connecting a manometer 40 to each orifice, the proper inclination being obtained when all of the manometers give identical readings.

Fig. 5 illustrates a form of orifice having a curved inlet 35 extending into the interior 45 of the pipe 21. This type of orifice may be adjusted by turning it so as to present various angles to the direction of flow within the pipe, and is very sensitive to fluctuations in the velocity of the brine.

50 By the application of the present invention to diaphragm cells having no overflow or equivalent constant-level device, an accurate and wholly automatic control of the percolation through the diaphragm is secured, 55 since the level of electrolyte within the cell will automatically vary in the direction and to the precise degree necessary to secure an average percolation equivalent to the inflow. Thereby a constant percentage of decomposi- 60 tion and a constant and high ampere efficiency is attained; while the maintenance of the saturation of the electrolyte leads to a relatively high energy efficiency. This result in the particular system chosen for illus-

tration is dependent upon the maintenance 65 of a constant level in the pressure-regulating tank 6; but it will be obvious to those skilled in this art that other means may be employed for accomplishing the same result.

The process described herein consisting in 70 supplying to an electrolytic cell an aqueous electrolyte carrying a salt in solid phase, the quantity of salt introduced in unit time being preferably proportioned to maintain approximate saturation of the electrolyte with- 75 in the cell, is broadly claimed in a copending application of Albert H. Hooker, Serial Number 401,391, filed Aug. 5, 1920.

We claim:

1. The combination with an electrolytic 80 cell of means for supplying electrolyte thereto; said means comprising an external circulating system for electrolyte; a feed orifice for the cell; and means included in said circulating system for maintaining a constant 85 head at said feed orifice.

2. The combination with an electrolytic cell of means for supplying electrolyte thereto; said means comprising an external circulating system for electrolyte; a feed orifice 90 for the cell; means included in said circulating system for maintaining a constant head at said feed orifice; and means for adjusting said feed.

3. The combination with a plurality of 95 electrolytic cells, of means for supplying electrolyte thereto; said means comprising an external circulating system for electrolyte; a feed orifice for each cell; and means included in said circulating system for maintaining a constant and substantially uniform 100 effective head at each of said feed orifices.

4. The combination with a plurality of electrolytic cells, of means for supplying electrolyte thereto; said means comprising an 105 external circulating system for electrolyte; a feed orifice for each cell; means included in said circulating system for maintaining a constant and substantially uniform effective head at each of said feed orifices; and means 110 for adjusting said feed.

5. The combination with an electrolytic cell, of means for supplying electrolyte thereto; said means comprising a circulating system for electrolyte; and means for supplying 115 salt in solid phase to the circulating electrolyte.

6. The combination with an electrolytic cell, of means for supplying electrolyte thereto; said means comprising a circulating system for electrolyte; and means for continuously supplying salt in solid phase to the circulating electrolyte.

7. The combination with a plurality of electrolytic cells, of a common feed pipe 125 therefor, and means for supplying electrolyte thereto at constant head; said feed pipe downwardly inclined in the direction of flow

of the electrolyte, whereby the flow to the individual cells is substantially equalized.

8. The combination with an electrolytic cell, of means for supplying thereto electrolyte carrying salt in solid phase, said means comprising an agitating device for maintaining the salt in suspension, a feed orifice for

the cell, and means for maintaining a constant head at said feed orifice.

In testimony whereof we affix our signatures.

THOMAS L. B. LYSTER.
